UNITED STATES PATENT OFFICE.

STEWART R. MCKAY, OF CLEVELAND, OHIO, ASSIGNOR TO MCKAY CONCRETE FORM COMPANY, OF SEWAREN, NEW JERSEY, A CORPORATION OF NEW JERSEY.

CONCRETE-FORM.

1,315,027.

Specification of Letters Patent.

Patented Sept. 2, 1919.

Original application filed June 12, 1915, Serial No. 33,798. Divided and this application filed September 13, 1916. Serial No. 119,850.

To all whom it may concern:

Be it known that I, STEWART R. MCKAY, a citizen of the United States, residing at Cleveland, in the county of Cuyahoga and 5 State of Ohio, have invented a certain new and useful Improvement in Concrete-Forms, of which the following is a full, clear, and exact description.

This invention relates to forms which are 10 employed for the purpose of molding concrete material, the invention shown herein being illustrated in connection with the construction of a wall, such as may be employed in the erection of buildings. The invention 15 relates more particularly to the construction and arrangement of the posts, panels and fastening means whereby the panels may be conveniently applied to and removed from the posts and may be efficiently retained in 20 operative relation to the work during the molding operation.

The invention herein disclosed is a division 25 of my application No. 33798 filed June 12, 1915.

In the drawings forming part hereof, Figure 1 represents a sectional detail in perspective of a post, a pair of panels and the clamping means employed for securing the latter to the posts; Fig. 2 an elevation, 30 with parts broken away, of the construction shown in Fig. 1; Fig. 3 a sectional plan view of the construction shown in Figs. 1 and 2; and Fig. 4 a plan view of a portion of a mold embodying my invention.

Describing by reference characters the various parts illustrated herein, 11 denotes generally one of the posts. Each post is preferably of pressed metal and comprises a hollow channel shaped body having tapered 40 side flanges 11^a provided with laterally extending flanges 11^b to which there is secured, in any convenient manner a plate 11^c, the lateral edges of said plate and the flanges 11^b forming lips or stop projections adapted 45 to coöperate with the panels in a manner to be described hereinafter. The side flanges 11^a merge with inwardly projecting shoulders 11^d from the proximate edges whereof there extends a U-shaped projection 11^e. 50 To strengthen the post, the plate 11^c is fitted between the rear ends of the flanges 11^a and is secured in place in any suitable manner to the shoulders or flanges 11^d.

The projection 11^e is provided with a suit-

able number of clamping members adapted 55 to coöperate with the lateral ends of panels on opposite sides of the posts. Each of these clamping members is shown as a block 12 which is pivoted to a stud 13 which may conveniently project between the branches 60 of the U-shaped extension 11^e from the plate 11^f. Each block 12 is pivoted to the stud 13, and the two clamping blocks are preferably supported from this stud in the same manner as the leaves of a butt hinge, as indicated 65 at 12^a. It is intended that the blocks 12 shall swing upward out of the way to permit the application of the panels to the flanges 11^b and then be swung downwardly to hold the panels in place. This action is 70 permitted by slotting the sides of the post extension 11^e. As will be evident from Figs. 1 and 2, these slots (indicated at 11^g) extend upwardly and downwardly from the pivotal support for the clamping blocks and 75 are preferably beveled at their upper ends, as indicated at 11^h, to permit the blocks to be swung entirely clear of the panels.

Coöoperating with the posts are the panels, indicated generally at 3. Each panel, as 80 illustrated, consists generally of a wooden body or filler 3^a having at each lateral end thereof a tongue 3^b with a shoulder 3^c extending in opposite directions from said tongue. Each panel is shown as provided 85 with a metal sheathing 3^d which covers both sides and the lateral ends thereof, conforming to the tongues 3^b and shoulders 3^c.

With the parts constructed and illustrated as described, the posts will be set up and may 90 be supported in spaced relation by means of ranger rods, such for instance as shown in my application No. 672,648 filed Nov. 17, 1914. When it is desired to apply a panel between a pair of posts, the blocks 12 are 95 folded up on their pivots and the panel applied between the posts with the sides of the tongues seated against the flanges 11^b. The blocks are then swung downwardly upon their pivots, engaging the rear or outer sides 100 of the tongues 3^b and thus holding the panels to their seats and in operative relation to the work, with the inner or rear faces of the panels and the inner or rear faces of the posts in substantially the same plane. When 105 it is desired to remove the panels, it is necessary only to swing the clamping blocks 12 upwardly on their pivots, whereupon the

panels may be moved outwardly. By beveling the lateral sides 11^a of the posts, an increasing clearance is provided between the ends of the panels and the posts as the 5 panels are moved outwardly, thus enabling the panels to be removed without adhesion to the concrete and especially to any that may have worked in between the lateral ends of the panels and the posts.

10 Having thus described my invention, what I claim is:

1. In a form of the character described, the combination, with a pair of spaced posts each having a rearwardly extending stud 15 and a seat between said stud and the forward or work-facing side thereof, of a clamping member pivoted to each stud and adapted to swing in a plane longitudinal of said post, and a panel adapted to be interposed between said posts and having a lateral extension at each end and between the inner and the outer face thereof adapted to be engaged on one side by the seat and on its opposite side by the coöperating 20 25 clamping member.

2. In a form of the character described, the combination, with a pair of spaced posts each having a stud, of a pair of oppositely extending clamping members independently 30 pivoted to each stud and adapted to swing in a plane longitudinal of said post, and a panel adapted to be interposed between said posts and to be engaged by the clamping member adjacent thereto.

35 3. As a new article of manufacture, a metallic post having at each lateral side

thereof a seat and a hollow rearward extension, a stud within said extension, the opposite sides of the extension being slotted, and a pair of clamping blocks pivoted on said 40 stud and extending in opposite directions through said slots.

4. As a new article of manufacture, a metallic post having at each lateral side thereof a seat and a hollow rearward extension, a stud within said extension, the opposite sides of the extension being slotted, and a pair of clamping blocks pivoted on said 45 stud and extending in opposite directions through said slots.

5. As a new article of manufacture, a metallic post having at each lateral side thereof a seat and a rearward extension comprising a pair of spaced plates, a stud extending at substantially right angles to the length of said post and interposed between said plates, and a clamping block pivoted to said stud and extending through a slot in one of said plates.

6. As a new article of manufacture, a 60 metallic post having at each lateral side thereof a seat and a rearward extension comprising a pair of spaced plates, a stud extending at substantially right angles to the length of said post and interposed between said plates, said plates being slotted, and clamping blocks pivotally connected to said stud and projecting through said slots.

In testimony whereof, I hereunto affix my signature.

STEWART R. MCKAY.
